Stanley M. Udale

ATTORNEY.

UNITED STATES PATENT OFFICE

GEORGE M. HOLLEY, OF DETROIT, MICHIGAN

HOT SPOT MANIFOLD

Application filed November 11, 1929. Serial No. 406,946.

This invention relates to a hot spot manifold adapted to be used with an internal combustion engine on an automobile over which a current of air flows from the front to the rear. The object of this invention is to provide heating means whereby the rate of heating up of the inlet manifold may be hastened, and to provide semi-thermostatic means which will automatically prevent the inlet manifold temperature rising to such a figure as will materially reduce the power. It is understood of course that no attempt is made to keep the mixture temperature even approximately constant as it is doubtful whether it is desirable to have an absolutely constant temperature, and in any event this invention does not produce that result.

Figure 1 shows the device in elevation.

Figure 2 shows a cross sectional elevation 20 of plane 2-2 of Figure 1.

Figure 3 shows a partial section elevation taken on the plane 3-3 of Figure 2 showing the thermostatic element.

Figure 4 shows the manifold mounted on 25 an engine having the usual radiator and cooling fan.

In the figures, A is the exhaust manifold having the outlet B to the rear, a current of air flows from the front of the exhaust manifold A to the rear, flowing from the radiator (not shown) being propelled by a fan (not shown). The arrows in Figure 1 indicate this flow of air over the exhaust manifold B. C is the inlet manifold having 30 a flange D to which a carburetor of any well known type is adapted to be connected. E is a valve in the exhaust outlet B, mounted on a shaft F to which is connected a link or crank G which is connected through a link H with a lever arm J, K (Figure 3) is the thermostatic element riveted to the lever J and connected to the shaft L, the thermostatic element is partly enclosed by a casing or cover M, this casing M is anchored to the 35 inlet manifold C by the screws N-N. The shaft L is threaded into the cover M and locked in place by the lock nut O. In order that the valve E can be assembled in the exhaust manifold A a cover P is provided 40 which is held in place by 3 cap screws. The

inlet manifold C is provided with a jacket Q which communicates with the exhaust manifold A. The exhaust enters the jacket Q through an opening R in the exhaust manifold A. The inlet manifold C is bolted to 55 the exhaust manifold by means of the cap screws U-U, a gasket being used to prevent leakage. S is a tube forming an outlet from the jacket Q this tube communicating with an opening T in the outlet B of the 60 exhaust manifold. The opening T is adapted to be closed by the valve E when E is rotated 90° in a clockwise direction from the position shown in Figure 1.

When the automobile to which the device 65 is applied, is started and the temperature of the air flowing over the exhaust manifold is below 90° F. then the valve E is in the position shown in Figure 1. The minute the engine begins to fire the exhaust gas escapes 70 via the passage RQST to the exhaust outlet B and the walls of the inlet manifold C are thereby heated. Heat immediately flows from C through the casing M to the thermostatic element K contained therein. As this 75 element K is made of two metals welded together the coil of metal unwinds and the lever J is rotated in an anti-clockwise direction about the center of the shaft L to which the element K is anchored. The shaft 80 L is threaded into M and is locked in place by the lock nut O. The temperature at which the lever J begins to move the valve E is therefore determined by the position to which the shaft L is turned when the nut O 85 is locked in place. The anticlockwise rotation of J turns the valve E in a clockwise direction, first opening the exhaust manifold A so as to permit some of the exhaust to escape direct to B and finally closing the outlet T from the pipe S, thus forcing all the 90 exhaust gases to flow directly to the exhaust outlet B.

What I claim is:

1. In combination with an automobile operated by an internal combustion engine, an exhaust manifold having an exhaust outlet located to the rear of said engine, an inlet manifold associated with said exhaust manifold, an exhaust jacket partially surrounding 95

said inlet manifold, said exhaust jacket communicating with said exhaust manifold, an outlet from said exhaust jacket communicating with the outlet from said exhaust manifold, a valve in said exhaust outlet adapted to close said outlet from said jacket and at the same time open the exhaust manifold directly to the exhaust outlet, and alternately open the said outlet from said jacket and close the exhaust manifold directly to the exhaust outlet, thermostatic means located entirely on the outside of said inlet manifold and connected with said valve for the purpose described.

15 2. In combination with an automobile operated by an internal combustion engine, an exhaust manifold having an exhaust outlet located to the rear of said engine, means for passing a current of air over said exhaust manifold from the front to the rear, an inlet manifold associated with said exhaust manifold, an exhaust jacket partially surrounding said inlet manifold, said exhaust jacket communicating with said exhaust manifold, an outlet from said exhaust jacket communicating with the outlet from said exhaust manifold, a valve in said exhaust outlet adapted to selectively obstruct and prevent the flow of exhaust gases from the exhaust manifold to the exhaust outlet and from the exhaust jacket to the exhaust outlet, thermostatic means located entirely on the outside of said inlet manifold so as to be heated thereby and located in the air stream flowing over the exhaust manifold, said thermostatic means being connected with said valve for the purpose described.

3. A thermostatic means for controlling the mixture temperature in an internal combustion engine comprising an inlet manifold, an exhaust manifold and an exhaust jacket partially surrounding said inlet manifold and communicating with said exhaust manifold, an outlet from said exhaust jacket, an outlet from said exhaust manifold, a double acting valve controlling the common outlet from said jacket and said exhaust manifold, said valve being adapted to alternately open the exhaust manifold directly to the exhaust outlet and at the same time close the exhaust jacket outlet and to alternately open the outlet from the exhaust jacket and close the outlet from the exhaust manifold, a casting bolted to the outside of the manifold, a shaft threaded therein, a thermostatic element located entirely on the outside of said inlet manifold and connected to said shaft, said shaft being adjustable with relation to the said cap, a lever connected to the said thermostatic element, link means connecting the lever with said double acting valve for the purpose described.

4. A thermostatic means for controlling the mixture temperature in an internal combustion engine comprising an inlet manifold,

an exhaust manifold and an exhaust jacket partially surrounding said inlet manifold and communicating with said exhaust manifold, an outlet from said exhaust jacket, an outlet from said exhaust manifold, a double acting valve controlling the common outlet from said jacket and said exhaust manifold, said valve being adapted to alternately open the exhaust manifold directly to the exhaust outlet and at the same time close the exhaust jacket outlet and to alternately open the outlet from the exhaust jacket and close the outlet from the exhaust jacket and close the outlet from the exhaust manifold, a casing bolted to the outside of the manifold, a shaft threaded therein, a thermostatic element in the form of a helix located entirely on the outside of said inlet manifold and connected to said shaft, said shaft being adjustable with relation to the said cap, a lever connected to the said thermostatic element, link means connecting the lever with said double acting valve for the purpose described.

5. An internal combustion engine having an exhaust pipe, an inlet manifold, an exhaust jacket partially surrounding said inlet manifold, said jacket being in communication with said exhaust pipe, a valve in the exhaust pipe controlling the flow of exhaust gases through said jacket, a thermostatic element located entirely on the outside of the inlet manifold, link means extending from said thermostatic element to the said valve whereby the flow of heat through said exhaust jacket is automatically restricted as the temperature of said thermostatic element is raised by the increase in the temperature of the inlet manifold and the temperature of the air surrounding said inlet manifold.

6. An internal combustion engine having an exhaust pipe, an inlet manifold, means for passing a current of air over said inlet manifold after said current of air has performed the function of cooling the engine, an exhaust jacket partially surrounding said inlet manifold, said jacket being in communication with said exhaust pipe, a valve in the exhaust pipe controlling the flow of exhaust gases through said jacket, a thermostatic element located entirely on the outside of the inlet manifold, link means extending from said thermostatic element to the said valve whereby the flow of heat through said exhaust jacket is automatically restricted as the temperature of said thermostatic element is raised by the increase in the temperature of the inlet manifold and the temperature of the air surrounding said inlet manifold.

In testimony whereof I affix my signature.

GEORGE M. HOLLEY.
